United States Patent Office

Des. 228,601
Patented Oct. 16, 1973

228,601

PICTURE FRAME

Peter J. Menini, 814 N. 2nd Ave.,
Maywood, Ill. 60153

Filed Apr. 3, 1972, Ser. No. 240,888

Term of patent 7 years

Int. Cl. D6—07

U.S. Cl. D6—244

FIG.1

FIG.2

FIG.3

FIG.4

FIG.5

FIG. 1 is a front elevational view of a picture frame embodying my new design;

FIG. 2 is a top plan view thereof;

FIG. 3 is a bottom plan view thereof;

FIG. 4 is a right side elevational view thereof; and

FIG. 5 is a left side elevational view thereof.

The back of the picture frame shown in FIGS. 1-5 is flat and unornamented.

I claim:

The ornamental design for a picture frame, as shown and described.
